A. PETRIE.

METHOD OF MANUFACTURING EXTENSIBLE SLIDE SUPPORTS FOR WARDROBE TRUNKS.

APPLICATION FILED MAY 24, 1919.

1,402,012.

Patented Jan. 3, 1922.

UNITED STATES PATENT OFFICE.

AUGUST PETRIE, OF WEST ALLIS, WISCONSIN, ASSIGNOR TO MILWAUKEE STAMPING CO., OF WEST ALLIS, WISCONSIN, A CORPORATION OF WISCONSIN.

METHOD OF MANUFACTURING EXTENSIBLE SLIDE SUPPORTS FOR WARDROBE TRUNKS.

1,402,012.

Specification of Letters Patent. Patented Jan. 3, 1922.

Application filed May 24, 1919. Serial No. 299,477.

To all whom it may concern:

Be it known that I, AUGUST PETRIE, a citizen of the United States, residing at West Allis, county of Milwaukee, and State 5 of Wisconsin, have invented new and useful Improvements in Methods of Manufacturing Extensible Slide Supports for Wardrobe Trunks, of which the following is a specification.

- 10 My invention relates to improvements in methods of manufacturing extensible slide supports for wardrobe trunks, clothes presses, and storage chambers of various kind, in which sets of slides are mounted 15 upon telescoping supports adapted to be extended from within the chamber when the door or lid is open, whereby the slides may be drawn out along said supports to separate and expose clothing, or other articles carried thereby, or pushed into the chamber to 20 carry the stored articles therein preparatory to closing the door or lid. The slides ordinarily travel in frictional contact with their supports, and rest loosely thereon so that 25 they can be removed at pleasure.

The object of this invention is to provide an improved method of manufacturing the telescopic slide supports, whereby the cost of manufacture may be reduced to a minimum, the procedure expedited, and a structure produced along which the slides may travel in frictional contact with the supports, and from one associated member to the next, smoothly and without encountering 30 obstructions or projections calculated to materially increase the resistance to the sliding movement.

My process will now be described with reference to the accompanying drawings, in 40 which—

Figures 1, 2, and 3 are plan views showing respectively three die forms into which blanks may be cut from sheet metal preparatory to constructing the outer or tubular 45 member of my improved slide support.

Figure 4 is a cross sectional view of a press, indicating suitable means for shaping the blank to form a tubular slide member.

Figure 5 is a horizontal sectional view of 50 a wardrobe trunk, showing a fragment of the lid, and also showing a pair of my completed slide supporting members in position for use, and with the tubular slide members partly extended.

Figure 6 is a fragmentary vertical sectional view of the same.

Figure 7 is a sectional view, drawn on line 7—7 of Figure 6.

Figure 8 is a detail sectional view, drawn on line 8—8 of Figure 6.

Figure 9 is a perspective view of a portion of the assembled structure shown in Figure 6.

Like parts are identified by the same reference characters throughout the several views.

This application is a companion application, and is a continuation in part of my former application for Letters Patent for wardrobe trunks, filed February 17th, 1917, 70 Serial No. 149,190, and renewed November 29, 1920, Serial Number 427,211.

In the practice of my improved process, I first take a piece of sheet metal of the desired gage or thickness, and cut therefrom 75 a blank having a generally rectangular form, but having one end provided with an edge margin which is oblique to the side margins of the blank, or which follows a line extending obliquely from such side margins. 80 For example, in Figure 1, the blank 1 has side margins 2 and 3, which are parallel, and one end margin 4 which is at right angles to the side margins, but the other end of the blank is provided with a V-shaped 85 recess, thereby forming two edge margins 5 and 6 which extend along lines oblique to the side margins 2 and 3 of the blank; although preferably the oblique edges 5 and 6 do not intersect the side margins, this end 90 of the blank having portions 7 which are also at right angles to the side margins 2 and 3.

In Figure 2, I have illustrated a similar blank 9, having parallel side margins 10 and 95 11, and one end margin 12 at right angles thereto, but with the other end margin beveled, i. e., cut obliquely in a straight line extending entirely across the blank from one side to the other, thus forming an 100 oblique edge 13.

In Figure 3, the blank 15 is of a generally rectangular form, except at one end where the corners are cut away to form oblique margins 17 and 18 at one end of the blank, 105 these margins converging toward the central portion of the blank in a manner to form a projecting point.

After cutting or preparing a generally rectangular blank with an oblique edge margin at one end, I then roll or press its longitudinally extending central portion into 5 cylindrical or tubular form, the side margins being brought into proximity, and into positions parallel with each other, but preferably turned outwardly until their flat faces are substantially parallel with each other, 10 as illustrated in cross section in Figure 4, thereby forming a tubular member 20, having a slot or longitudinal opening along one side, flanked by outwardly projecting flanges 21 and 22, composed of the marginal 15 portions of the blank. The blank may be easily pressed into this shape by applying it to a die 24 with its longitudinal central portion registering with the concave or semi-cylindrical die cavity 25, and then forcing 20 it into the cavity by subjecting it to the pressure of a punch, having a substantially cylindrical head 26, and an upwardly projecting wing flange 27, the margins of the blank being then pressed into conformity with the 25 upper surfaces of the punch head, and with the sides of the wing flange, by horizontally moving press blocks 28, closing in upon the flange from the respective sides.

Assembly.

30 The squared end of the blank is then provided with a suitable head piece 30, which may comprise a narrow strip of sheet metal bent in the arc of a larger circle than that 35 which follows the wall of the blank, and the end portions of this head piece may be secured to the flanges 21 and 22 of the shaped blank by welding or riveting the head piece extremities to these flanges at 31. The blank 40 is then mounted upon a rod 35, which fits within its cylindrically curved portions, and it is so positioned upon the rod that one or more of the oblique edge margins 5, 6, or 13 will extend from the upper side of the rod 45 along a helical line downwardly and in the direction of the exterior, or end portion, of the rod in a position to form an inclined skid-way, along which a slide supported on the rod may travel to a position of support 50 upon the tubular member formed from the blank, as above described. The parts are held in this position by a supporting bracket 36, which is secured to the rod, and projects outwardly through the slot between the 55 flanges 21 and 22. This bracket I preferably utilize to connect the rod to one wall of the trunk or chamber to which my slide support is applied, this connection being illustrated at 38 in Figure 8.

60 I preferably support the exterior end of the rod 35 by securing it directly to the rim wall of the chamber, as shown at 40 in Figures 5, 6, and 7. A pair of slide supports thus secured to the wall of a trunk or other 65 chamber may be used to support a series of

slides 41 in positions to travel along their upper surfaces, and upon the helically inclined skid-ways formed by the oblique margins 5, 6, and 13 and 18.

It will be observed in Figure 5, which 70 shows a set of slide supports formed from blanks like those illustrated in Fig. 1, that the tubular portion of the blank has what might be termed a downwardly and inwardly beveled inner end, the edge margins 75 diverging from the upper side along oppositely curving helical lines on the respective side of the rod 35. It is not material, however, whether the oblique margins follow two helical lines or only one.

80 While I have emphasized the importance of providing the blank with an oblique edge at one end for the purpose of providing an inclined skid-way for the slide, I do not limit the scope of my invention to necessarily include this step as an absolutely essential part of my process, an extremely important portion of my invention being in the simple and inexpensive means whereby I 85 form a flat blank of sheet metal and convert 90 it into a tube having a slot along one side, flanked by outwardly projecting flanges.

95 By utilizing a cross pin 42 to connect the marginal flanges of the tubular member with each other at the inner side of the bracket 95 36, I may not only reinforce these flanges from each other, but I also provide a stop to prevent the tubular slide member from being wholly withdrawn from the rod.

I claim:—

100 1. The process of making enclosing tubular members for slide supports, consisting in forming a generally rectangular sheet metal blank, providing the same with an oblique end margin, and pressing the central portion of the blank into tubular form about a longitudinally extending axis and in a direction to cause the oblique end margin to 105 follow a helical line leading to a point between the ends of the tubular member on 110 the opposite side thereof from that toward which the side margins of the blank are 115 pressed, whereby said oblique margin may facilitate movement of other articles into a supported position upon the tube.

120 2. The process of making enclosing tubular members for slide supports, consisting in forming a generally rectangular sheet metal blank, providing the same with an oblique end margin, pressing the central portion of the blank into tubular form about a longitudinally extending axis, and also pressing the side margins of the blank outwardly in 125 parallel planes, and in spaced relation to each other, said tubular member being adapted to be mounted with its axis substantially horizontal and with said blank margin leading to a point in its upper surface to facilitate the movement of supported articles over the end of the member.

130

3. The process of making tubular members for slide supports, which consists in providing an elongated steel sheet metal blank with an oblique end margin, and bending the blank into tubular form, said blank being adapted to be telescoped upon a rod and to be supported substantially horizontally in a position to cause said oblique margin to cross said horizontal plane which includes a portion of the tubular member between its axis and its upper surface to facilitate the movement of supported slides from the rod to the tubular member.

5 In testimony whereof I affix my signature in the presence of two witnesses. 15

AUGUST PETRIE.
